UNITED STATES PATENT OFFICE.

FRED CLAYTON, OF STRINES, ENGLAND, ASSIGNOR TO JAMES JONES
MELDRUM, THOMAS FREDERICK MELDRUM, AND JOHN WESLEY
MELDRUM, OF MANCHESTER, ENGLAND.

FURNACE.

SPECIFICATION forming part of Letters Patent No. 655,759, dated August 14, 1900.

Application filed December 28, 1897. Serial No. 664,025. (No model.)

To all whom it may concern:

Be it known that I, FRED CLAYTON, a subject of the Queen of England, and a resident of Strines, England, have invented certain 5 new and useful Improvements in Furnaces, of which the following is a specification.

This invention has reference to furnaces having moving fire-bars mechanically operated.

10 The invention is illustrated in the annexed drawings.

In the drawings, Figures 1 and 2 illustrate the formation of the ends of two adjacent fire-bars detached; and Figs. 3, 4, 4^A, 4^B, and 15 4^C show the same working together and in connection with cams, hereinafter described, the latter and the ends of the fire-bars being so formed that only two cams are needed for each pair of fire-bars.

20 The two cams *a* and *a'*, Figs. 3 to 4^C, are fixed closely side by side or made in one piece and are threaded alternately upon the hexagonal or other suitably-shaped shaft *c*. (See Fig. 1.) These cams work, respectively, in 25 spaces or jaws *d* *d'*, made in the ends of the two fire-bars, as shown in Figs. 1 to 4, the different positions being more clearly shown in Figs. 4^A, 4^B, and 4^C. One cam *a* is in the form of a single ratchet, catching against 30 one or two projections *e* *e'* on its corresponding fire-bars *f* to move the same in one direction or the other. The second cam *a'* is in the form of a sector of a circle or is otherwise so formed that as the first cam *a* is drawing 35 its bar *f* outward it holds the second bar *f'* in place by working against the curved part *d'* of the jaw, at the end of the same, should the outward motion of the first bar tend to draw it back, and while the first cam 40 *a* is moving from one projection *e* to the other on the first bar *f* (see Figs. 4^A, 4^B, and 4^C) the second cam *a'* withdraws the second bar *f'*,

which is so formed with a recess at *d*³ that one side of the sector or cam *a'* will catch against it at this part of the revolution of the 45 cam-shaft. The first bar *f* is in some cases provided with a projection *g*, (see Fig. 3,) which when both bars are withdrawn bears against part of the outer end of the second bar *f'*, so that as the former is pushed inward or forward by its cam it will carry the second bar with it; but I do not claim this projection *g* as any part of my invention, for by making the cam *a* sufficiently wide, as shown in Fig. 4, the same cam *a* will act upon the lower 55 jaws of both bars, and the projection *g* is therefore unnecessary.

What is claimed in respect of the herein-described invention is—

1. In a furnace having moving fire-bars, 60 mechanically operated, the combination with a pair of fire-bars, of double cams, adapted to operate upon the end of the bars, and one of said cams being in advance of the other, and the trailing cam adapted to act as a stop 65 to its bar, while the other is in action and drawing its bar forward; substantially as set forth.

2. In a furnace having moving fire-bars mechanically operated, the combination of a 70 pair of bars *f* *f'* having jaws *d* *d'*, respectively, and the cams *a* *a'* in advance of each other, and adapted to act upon the bars *f* and *f'* respectively, in succession, the cam *a'* acting as a stop to its bar while cam *a* is in action and drawing its bar forward; substantially as set forth.

In testimony whereof I have hereunto set my hand in presence of two subscribing witnesses.

FRED CLAYTON.
